MACHINE FOR BOTTLING LIQUIDS UNDER PRESSURE.

1,045,567.

Specification of Letters Patent.

Patented Nov. 26, 1912.

Application filed November 1, 1911. Serial No. 658,027.

To all whom it may concern:

Be it known that I, JOHANNES KARLSSON LANNMARK, a subject of the King of Sweden, residing at Stockholm, in the Kingdom of Sweden, have invented new and useful Improvements in Machines for Bottling Liquids Under Pressure, of which the following is a specification, reference being had to the drawings accompanying and forming a part hereof.

This invention relates to machines for bottling liquids under pressure.

One of the principal features of my invention is an air receiver placed inside the receiver for the liquid and provided with a passage which leads to the interior of a bottle when in position to be filled, means for discharging the air from the receiver before a second bottle is placed in position to be filled, and means for tightening around the neck of the bottle.

The chief object of the invention is to compensate for the decrease in volume of the liquid in the vessel from which the liquid is drawn off, so that the pressure within the said vessel and the bottle to be filled communicating with said vessel remains unaltered during the filling operation.

The bottle to be filled is suitably connected to a slide by means of tightening devices around the neck of the bottle and adapted to reciprocate between two working positions, so that the bottle, after having been filled, may be moved into a second position where it can be corked.

The invention further comprises the construction and combination of parts herein-after set forth.

In the drawing, I have shown a part of a bottling and corking machine embodying the invention.

Figure 1 is a sectional view showing a part of the receiver for the liquid, the air receiver, the filling pipe and means for tightening around the neck of the bottle. Fig. 2 is plan view of Fig. 1. Fig. 3 and 4 are sectional views showing, to a larger scale, two different constructional forms of the tightening device.

Referring to the drawing, 1 is a table and 2 is a filling vessel or receiver communicating with the tank or receiver (not shown) in which the liquid is contained and exposed to gas-pressure. The receiver 2 opens into a series of tubes 3, each communicating

with a sleeve 4 tightly surrounding a vertically movable tap or filling pipe 5 adapted to reciprocate lengthwise through the sleeve 4 and having a longitudinal slot communicating with the tube 3, when the filling pipe 5 is lowered by means of a suitable driving mechanism (not shown). The pipe 5 passes through an opening 7 in the table 1, said opening being provided with a suitable sleeve or packing box 6 insuring a tight passage for the pipe 5. The table 1 further has an opening 8 for a vertical driver 9 to be used in connection with a corking mechanism forming no part of the present invention. Further the table 1 has a passage 14 leading from the opening 7 to a resilient or compressible vessel or receiver 15 placed within the receiver 2. To the uppermost part 15^a of receiver 15 is attached a pipe 15^b adapted to slide up and down in a pipe 15^c connecting the interior of receiver 15 with passage 14. The pipe 15^b is provided with a longitudinal slot or perforations (not shown) extending from the lowermost to the uppermost part of pipe 15^b, so that the interior of the receiver 15 in every position of pipe 15^b within pipe 15^c always communicates with the passage 14. The passage 14 also communicates with an opening 31 in the table 1, said opening 31 being normally shut off by a slide 19 placed on the lower side of the table 1 and adapted to be reciprocated lengthwise by means of a suitable driving mechanism (not shown). The slide 19 has an opening 20 corresponding with the openings 7 and 8.

Placed beneath the opening 20 is a downwardly projecting cup 21 for the mouth of the bottle, and placed in the said cup is an elastic ring or the like 22 adapted to be filled with compressed air or water for a suitable supply, so as to tighten around the neck of the bottle. As shown in Fig. 3 the ring 22 may be solid in which case the cavity 22^b receiving the air or water is formed by the solid ring 22 and an outer ring 22^a tightly surrounding the ring 22 and preferably made of inflexible material. Fig. 4 shows a ring 22 made of elastic material and in which the cavity 22^b is formed in the material of the ring 22 itself. The cavity 22^b and the ring 22 may be connected with an inflating mechanism or water supply of any suitable kind.

When the slide 19 is in its initial position

shown in Fig. 1, the opening 20 is directly under the opening 7. By means of a suitable lifting device (not shown) the bottle is lifted and the bottle mouth placed into the 5 cup 21. The cavity 22^b, after having been filled with gas or water, causes the ring 22 to tighten against the neck of the bottle. The filling pipe 5 now descends through the openings 7 and 20 into the bottle, and the 10 communication between this pipe and the receiver 2 opens, so that the bottle can be filled with liquid. The air contained in the bottle is compressed and flows through the opening 20 outside the pipe 5, the opening 7 into the 15 vessel 15, which is used for equalizing the pressure in the bottle and in the receiver 15 during the filling operation. The pipe 5 thereupon ascends above the slide 19, whereby by the communication between the said pipe 20 and receiver 2 is shut off. The slide 19 moves into a position in which the opening 20 is just below the opening 8 and the air compressed in the vessel 15 now escapes through the opening 31 which is uncovered 25 by the said movement of the slide 19. The receiver 2 is filled with liquid under pressure according as the receiver 15 is emptied.

During the movement of the slide 19 the bottle is suspended under the opening 20 and is retained in this position by the ring 22. By means of the driver 9 descending through the openings 8 and 20 the corking of the bottle then is effected. After the bottle is corked, the cavity 22^b is emptied, so 35 that the bottle can be released from the slide 19. After the driver 9 has again ascended, the slide returns, and the parts have then resumed their initial positions.

Certain parts of the machine may be 40 modified without altering the nature of the invention. Thus, for instance, the pipe 5 may be rigidly connected to the receiver 2, which in this case is movable in a vertical direction. In this case the pipe 5 may be 45 provided with a valve to be operated from without, and the passage 14 may be connected to the compressible vessel 15 by means of a flexible hose or conduit.

Having now described my invention, what 50 I claim as new and desire to secure by Letters Patent is:

1. In a machine for bottling liquids under pressure, the combination of a receiver for the liquid, a compressible air receiver placed 55 inside and separated from the said receiver for the liquid and connected with the interior of a bottle when in position to be filled, and means for discharging the air from the said compressible air receiver before a second bottle is placed in position to be filled.

2. In a machine for bottling liquids under pressure, the combination of a receiver for the liquid, means for connecting the said receiver with a bottle when in position to be 65 filled, a compressible air receiver placed in-

side said receiver for the liquid and exposed to the pressure within the same, said air receiver exerting a counter-pressure on the liquid in the liquid receiver, a connection between the said air receiver and the interior 70 of the bottle, and means for allowing the air within the air receiver to discharge before a second bottle is placed in position to be filled.

3. In a machine for bottling liquids under pressure, the combination of a receiver for 75 the liquid, an air receiver placed inside the said receiver for the liquid, and connected with the interior of a bottle when in position to be filled, means for tightening around the neck of the bottle, means for shifting 80 the bottle from its filling position into a second position, while maintaining the tightening around the neck of the bottle so as to prevent the pressure within the bottle from being destroyed, and means for discharging 85 the air within the air receiver during the said shifting movement.

4. In a machine for bottling liquids under pressure, the combination of a receiver for the liquid, means for connecting the said 90 receiver with a bottle when in position to be filled, means for tightening around the neck of the bottle, a compressible air receiver placed inside the receiver for the liquid and exerting a counterpressure on the liquid 95 therein, a connection between the said air receiver and the interior of the bottle, means for shifting the bottle from its filling position into a second position, while maintaining the tightening around the neck of the bottle so as to prevent the pressure within the bottle from being destroyed, and means for discharging the air within the air receiver during the said shifting movement.

5. In a machine for bottling liquids under 105 pressure, the combination of a receiver for the liquid, a movable filling pipe adapted to enter into the bottle when in position to be filled and communicating, in its filling position, with the said receiver, means for tightening around the neck of the bottle, a compressible air receiver placed inside the receiver for the liquid and exposed to the pressure therein, said air receiver exerting 110 a counterpressure on the liquid in the liquid receiver, and a connection between the interior of the bottle and the said air receiver.

6. In a machine for bottling liquids under 120 pressure, the combination of a receiver for the liquid, a movable filling pipe adapted to enter into the bottle and communicating, in its filling position, with the said receiver, a compressible air receiver placed inside the receiver for the liquid and exerting a counterpressure on the liquid therein, a 125 table having an opening for the filling pipe and a passage communicating with the said opening and with the interior of the air receiver, a slide movable along the said table and having an opening corresponding to the 130

opening in the table, and means carried by the said slide for tightening round the neck of the bottle.

7. In a machine for bottling liquids under pressure, the combination of a receiver for the liquid, a movable filling pipe adapted to enter into the bottle and communicating in its lowered position with the said receiver, means for tightening around the neck of the bottle, a compressible air receiver placed inside the receiver for the liquid, and a connection between the interior of the bottle and the said air receiver.

8. In a machine for bottling liquids under pressure, the combination of a receiver for the liquid, a movable filling pipe adapted to

enter into the bottle and communicating, in its filling position, with the said receiver, a compressible air receiver placed inside the receiver for the liquid, a table having an 20 opening for the filling pipe and a passage communicating with the said opening and the interior of the air receiver, a slide movable along the said table and having an opening corresponding to the opening in the 25 table, and means carried by the said slide for tightening around the neck of the bottle.
